UNITED STATES PATENT OFFICE.

COURTNEY H. WEST, OF ST. LOUIS, MISSOURI, ASSIGNOR TO THE MOFFITT-WEST DRUG COMPANY, OF SAME PLACE.

DESIGN FOR A BOTTLE.

SPECIFICATION forming part of Design No. 23,891, dated December 25, 1894.

Application filed November 27, 1894. Serial No. 530,183. Term of patent 14 years.

To all whom it may concern:

Be it known that I, COURTNEY H. WEST, a citizen of the United States, residing at the city of St. Louis, State of Missouri, have invented a certain new and original Design for Bottles, of which the following is a full, clear, and exact description, reference being had to the accompanying drawings, forming a part of this specification, wherein—

10 Figure 1 is a side elevational or face view of a bottle ornamented and configured according to my new design. Fig. 2 is an edge elevational view, and Fig. 3 is a cross-sectional view.

15 In the drawings A indicates the body of the bottle, the cross-section of which is illustrated in Fig. 3, which cross-section is preserved from the bottom, upwardly for some distance, when the side lines are curved inwardly and upwardly forming substantially an apex, from which projects a cylindrical neck B, which neck is formed at its upper edge with the circular flange b forming the mouth of the bottle. On both side faces of the body portion, 20 are formed raised panels C, whose upper ends are formed with apices. Surrounding these panels C, but terminating at the bottom of the body portion, are curved portions D, which

connect the panels C with the edge bands E. These curved portions D are ornamented with 30 a series of scrolls, which extend over the entire length of the same; said scrolls meeting each other at their ends. The edge bands E run from the curved portions D on each side of the bottle to an apex, the two side faces of 35 which form substantially an obtuse angle to each other the meeting point of which divides the body into substantially two halves. The molding or curved portions D, follow the general outline of the panels C, the apices 40 of which moldings are curved or blunted as shown. The edge bands E extend from the bottom of the bottle, defining the side lines, and terminate at the neck about on a line with the apices of the moldings D. 45

What I claim is—

The design for a bottle, substantially as herein shown and described.

In testimony whereof I hereunto affix my signature, in presence of two witnesses, this 50 16th day of November, 1894.

COURTNEY H. WEST.
